UNITED STATES PATENT OFFICE.

LOUIS LUNDSTROM, OF LOS ANGELES, CALIFORNIA.

DESIGN FOR A MATCH-SAFE.

41,923.

Specification for Design.

Patented Nov. 14, 1911.

Application filed August 30, 1911. Serial No. 646,939. Term of patent 7 years.

To all whom it may concern:

Be it known that I, LOUIS LUNDSTROM, a citizen of the United States, residing at Los Angeles, in the county of Los Angeles and State of California, have invented a new, original, and ornamental Design for Match-Safes, of which the following is a specification, reference being had to the accompanying drawing, forming part thereof.

The figure is a plan view of a match safe, showing my new design.

I claim:

The ornamental design for a match safe as shown.

LOUIS LUNDSTROM.

Witnesses:

EDITH STADLMAN,
EARLE R. POLLARD.
